UNITED STATES PATENT OFFICE.

LEONARD V. MIDDLESWORTH, OF PHILADELPHIA, PENNSYLVANIA.

METAL-SASH JOINT.

1,108,511.

Specification of Letters Patent. Patented Aug. 25, 1914.

Application filed December 2, 1913. Serial No. 804,195.

To all whom it may concern:

Be it known that I, LEONARD V. MIDDLESWORTH, a citizen of the United States, residing at Philadelphia, in the county of Philadelphia and State of Pennsylvania, have invented certain new and useful Improvements in Metal-Sash Joints, of which the following is a specification.

My invention relates to improvements in metal sash joints, the object of the invention being to provide an improved construction of joint in which the muntins located at right angles to each other are securely locked together forming a neat juncture and insuring an extremely strong sash.

A further object is to provide the muntins with improved arrangement of recesses in their webs, so that when the webs are forced together when at right angles, a portion of one web will be bent so as to interlock in the recess in the other web.

With these and other objects in view, the invention consists in certain novel features of construction and combinations and arrangements of parts as will be more fully hereinafter described and pointed out in the claims.

In the accompanying drawings: Figure 1 is a fragmentary view in elevation illustrating my improved joint. Fig. 2 is a fragmentary view in side elevation of one of the muntins. Fig. 3 is a view in section on the line 3—3 of Fig. 2. Fig. 4 is a view in section on the line 4—4 of Fig. 2. Fig. 5 is a view similar to Fig. 2 illustrating the other muntin. Fig. 6 is a view in section on the line 6—6 of Fig. 5. Fig. 7 is a view in section on the line 7—7 of Fig. 1.

1 and 2 represent the two muntins located at a right angle to each other and forming my improved joint. Both muntins consist of webs 3 having integral beads 4 at one edge. The beads 4 project at both sides of the webs, and each bead at both sides of the web is recessed as shown at 5. These recesses are cut at an angle, so that when the muntins are crossed, they will nicely fit together with the lines of juncture at an angle of ninety degrees (90°) to each other. The muntin 1 is provided with a transverse slot 6 extending inwardly into the webbed portion and at its inner end having a lateral recess 7, the walls of the recess curved and merging into the walls of the slot. The muntin 2 is provided with a slot 8 cut into its web portion and forming at the inner end

of the slot, a locking tongue 9. This locking tongue is curved transversely and also at its free end, and in forming the slot the die used to cut the same will cut at a bevel 60 or incline so that the locking tongue will be relatively thin at its free end and gradually increase in thickness to its other end.

By curving the tongue transversely, the metal is appreciably weakened at both edges 65 of the tongue so that when the muntins are forced, the tongue will follow the curved wall 10 joining the slot 6 and recess 7, and will be bent into the recess 7 and securely lock therein as clearly shown in Fig. 7. 70

In operation, it is simply necessary to position the muntin 2 across the muntin 1 with the slot 8 registering with the slot 6, then forcing the muntin 2 inwardly. The tongue 9 is compelled to bend into the recess 7 and 75 securely lock the muntins together, insuring a strong durable juncture.

Various slight changes might be made in the general form and arrangement of parts described without departing from my invention, and hence I do not limit myself to the precise details set forth, but consider myself at liberty to make such changes and alterations as fairly fall within the spirit and scope of the appended claims. 80 85

Having thus described my invention, what I claim as new and desire to secure by Letters Patent is:

1. In a joint of the character described, the combination of two muntins located at 90 an angle to each other, one muntin having a slot therein with a recess at the inner end of the slot, and the other muntin having a tongue to enter the slot and lock in the recess, substantially as described. 95

2. In a joint of the character described, the combination with two muntins located at an angle to each other, one muntin having a slot therein with a recess at the inner end of the slot, and the other muntin having a 100 bendable tongue adapted to be bent into the recess and lock the muntins together, substantially as described.

3. In a joint of the character described, the combination of two muntins adapted to 105 be positioned at an angle to each other, each muntin comprising a web having a bead at one edge extending at both sides of the web, said beads recessed at both sides of the webs, one of said muntins having a 110 slot extending inwardly from the webbed edge and at its inner end having a recess in

one wall, the other muntin having a slot in its web portion with a tongue formed at the inner end of the slot, said tongue adapted to be bent laterally when the muntins are forced together and projected into the recess, substantially as described.

4. In a joint of the character described, the combination of two muntins adapted to be positioned at an angle to each other, each 10 muntin comprising a web having a bead at one edge extending at both sides of the web, said beads recessed at both sides of the webs, one of said muntins having a slot extending inwardly from the webbed edge and 15 at its inner end having a recess in one wall, the other muntin having a slot in its web portion with a tongue formed at the inner end of the slot, said tongue thinnest at its free end and tapering to its other end, and 20 said tongue curved transversely whereby the tongue at its sides is fragilely connected to

the web and adapted to be bent into the recess in the other muntin and lock the muntins together, substantially as described.

5. In a sash joint of the character described, the combination of two muntins, both muntins having slots in their edges of a width to receive the other muntin, one muntin having a recess at the inner end of its slot and the other muntin having a tongue at the inner end of its slot adapted to be bent into the recess when the muntins are forced together, substantially as described. 25 30

In testimony whereof I have signed my name to this specification in the presence of two subscribing witnesses.

LEONARD V. MIDDLESWORTH.
